AIR SEPARATOR

Thomas J. Sturtevant, Wellesley, Mass., assignor
to Sturtevant Mill Company, Boston, Mass., a
corporation of Massachusetts

Application July 14, 1930. Serial No. 467,716

5 Claims. (Cl. 209—139)

The invention to be hereinafter described relates to air separators for grading materials.

The invention is embodied in a separator of the type in which the classification is accomplished by an air current moving upward in a separating chamber and downward in a settling chamber. The air current is induced by a fan and caused to circulate through the chambers, and in its course passes through an inlet opening between the upper and lower shells forming the casing of the separating chamber. The materials to be graded are fed through a hopper into the separating chamber and are received by a rotary distributor which throws the materials out across the rising air current under the influence of centrifugal force. The lighter particles are carried upward by the air current through an outlet opening over into the settling chamber where they gravitate downward and are delivered therefrom, while the heavier particles or tailings gravitate downward through the rising air current in the separating chamber and are delivered therefrom.

As large a percentage as possible of fines of the desired size should be separated from the tailings, but if the velocity of the upward component of the whirling air current is sufficiently great thoroughly to clean such fines from the tailings, there is liability that tailings will be carried along with the fines from the separating chamber into the settling chamber. A purpose of the present invention therefore, is to provide means which will obstruct passage of tailings from the separating chamber into the settling chamber, and permit the velocity of the upward component of the air current to be sufficiently high for more efficient separation of the fines from the tailings and greater capacity of operation than heretofore possible in this class of work. To accomplish this, a rotary screen is provided in the separating chamber, and is so located with relation to the outlet opening of said chamber as to obstruct passing of heavier particles through the outlet opening, and deflect them toward the wall of the separating chamber, where they may gravitate downward and be discharged.

It is desirable that this separator shall be capable of classifying various materials with different degrees of fineness of product. The size of the openings of the rotary screen is fixed. Therefore, in order that within a limited range various products may be obtained, provision is made for varying the inlet and outlet openings, thereby to control the velocity and volume of the air cir-

culating through the chambers, the screen and the inlet and outlet openings.

As stated, the materials are fed into the separating chamber and received by a rotary distributor. It is desirable that materials shall be delivered from the distributor into several zones between the distributor and the wall of the separator, in order that the materials may be thoroughly disseminated in the rising air current. The more the materials may be opened and spread out, the more readily the classification will be accomplished. Another purpose of the present invention, therefore, is to provide a distributor which is designed to deliver materials from the perimeter thereof at varying distances from the axis of rotation of the distributor, and hence under varying degrees of centrifugal force.

The character of the invention may be best understood by reference to the following description of an embodiment thereof shown in the accompanying drawings, wherein:

Fig. 1 is a vertical longitudinal section through an air separator embodying the invention;

Fig. 2 is a horizontal section taken on line 2—2 of Fig. 1;

Fig. 3 is a horizontal section taken on line 3—3 of Fig. 1 showing the under face of the combined baffle and screen;

Fig. 4 is a vertical section taken on line 4—4 of Fig. 3;

Fig. 5 is a horizontal section taken on line 5—5 of Fig. 1; and

Fig. 6 is a horizontal section taken on line 6—6 of Fig. 1 showing the valve with its plates in positions of innermost adjustment.

Referring to the drawings, the separator shown therein as one good embodiment of the invention, comprises an outer casing 1 consisting of a drum 3 having a head 5 at the upper end thereof, and a cone 7 at the lower end thereof terminating in a discharge spout 9. Within and spaced from the outer casing is an inner casing 11 consisting of a drum 13 having a head 15 at the upper end thereof with an outlet opening 17 therein, and a conical shell 19 at the lower end thereof. This inner casing is supported by brackets 21 between and secured to the drums 3 and 13.

Beneath and spaced from the conical shell 19 is a conical shell 23 provided with a discharge spout 25 which extends laterally through an opening in the cone 7 of the outer casing. The conical shell 23 is supported by plates 27 secured to angle bars 29 and 31 respectively secured to the cones 7 and 23.

In the inner casing is the separating chamber

33, and between the inner and outer casings is the settling chamber 35. The space between the conical shells 19 and 23 serves as an inlet opening for the passage of air from the settling chamber into 5 the separating chamber. Located at this space is a series of vanes 37 having flanges 39 at the upper ends thereof pivotally connected to a ring 41 secured to and projecting outward from the lower edge of the conical shell 19.

10 To adjust these vanes to vary the opening at the inlet, the vane flanges carry and are pivotally connected to a ring 43. A rod 45 is pivotally connected to the ring 43, and has a portion extending through a sleeve bracket 47 secured to the outer casing drum 3. A hand wheel 49 is mounted on the bracket and is threaded to the rod 45, and is confined against movement axially of the rod. Rotation of the hand wheel will adjust the rod longitudinally thereof, and thereby impart 15 rotational adjustment to the ring 43 to vary the size of the spaces between the vanes. These vanes and the means for adjusting the same may be similar to the construction disclosed in my United States Patent No. 1,783,361 dated January 6, 20 1931.

To vary the outlet opening 17 in the head of the inner casing, a valve may be provided comprising a series of overlapped plates 51 resting upon the head of the inner casing and connected 30 to radial bars or handles 53 which extend outward through brackets 55 secured to the outer casing. These handles may be adjusted exteriorly of the outer casing in order to vary the size of the opening. This valve may be similar to 35 that disclosed in Letters Patent No. 1,615,558, granted to me January 25, 1927.

The materials to be graded are conducted into the separating chamber through an upper hopper 57 and through a conical hopper 59 extending 40 down through the outlet opening in the head of the separating chamber. Mounted on the head of the outer casing are channels 61 supporting the housing 63 having bearings in the upper and lower ends thereof. A vertical shaft 65 is journalled in said bearings, and has a bevel gear 67 fast thereon meshing with a bevel pinion 69 on the horizontal shaft 71 journalled in a bearing carried by the housing and in an outer bearing 73 carried by a transverse channel 75 on the 50 channels 61. At the outer end of the shaft 71 is a pulley 77 which may be driven from any suitable source of power.

The shaft 65 projects down through the hopper 59 into the separating chamber, and carries a 55 rotary distributor 79 comprising a plate hub 81 and segmental plates 83 secured thereto having depending flanges 85. These plates have straight outer edges 87, and the assembly has a polygonal perimeter. Projecting up from the plate hub of the rotary distributor are posts 89 carrying a hub 91 having lower and upper collars 93 and 95. Projecting up from and secured to the collar 95 are arms 97 carrying fan blades 99 in a chamber 101 between the heads of the outer and inner casings. 60 Mounted on and secured to the fan hub flange 93 is a plate or baffle 103 formed of sections secured together and having upstanding flanges 105.

An important feature of the invention is the 70 rotary screen referred to. In the present instance the screen is in the form of a ring 107 bolted to the margin of the baffle plate 103, and consists of sections 109 bolted together. Preferably this ring extends from the baffle plate nearly to the wall 75 of the separating chamber.

In operation, the materials to be graded are

fed through the hoppers 57 and 59 to the rotary distributor, and are whirled and thrown outwardly therefrom under the influence of centrifugal force. The materials are delivered from the perimeter of the distributor at various distances from the axis thereof. For example, the materials leaving the straight edge 87 of a distributor segment adjacent the ends of said edge, will leave the distributor at greater distances from its axis than materials delivered therefrom midway between the ends of said edge. As a consequence, the materials will be projected into zones between the distributor and the inner casing drum 13 at various distances from the distributor, and the materials will be desirably disseminated into the path of the whirling rising air current in the separating chamber.

The materials carried upward by the air current will strike the rotary screen. The fines will pass therethrough and through the outlet opening over into the settling chamber where they will be delivered through the spout 9. Heavier particles reaching the rotary screen will be obstructed and deflected outwardly thereby toward the wall of the separating chamber, and will gravitate downward adjacent said wall and be delivered through the spout 25. The openings in the screen preferably are substantially larger than the fines passing therethrough, so that there will be no liability of clogging of said openings by the fines. Heavier particles pass over the screen tangentially or transversely to the plane thereof, and therefore the openings effective in preventing passage of the heavier particles therethrough are smaller than the actual openings. 100 The sweep of the heavier particles past these openings is a further factor in contributing to maintaining them in open condition.

The baffle plate 103 is of the usual size relatively to the distributor 79, its diameter being 105 such that its peripheral edge lies below the outer edge of the central outlet 17. The perforated plate ring 107, forming the rotary screen, extends from the periphery of the baffle plate nearly to the wall of the separating chamber and thus 120 lies below the cover 15 of the separating chamber. This relation of the parts is important in maintaining the classification for which the screen is designed. Such heavier particles as do pass the screen are projected against the cover 15, 125 or at least into the more or less dead air space at the upper corner of the separating chamber whereupon they fall back upon the rotating screen and are shot outward to the wall and pass downward between the screen and the wall 130 to join like particles that have been separated from the fines below the rotary screen.

As stated, it is desirable that the separator shall have the capacity of classifying materials of varying character and varying sizes of fines. 135 The openings in the rotary screen are of fixed size, but by adjusting the vanes at the inlet opening and the valve at the outlet opening, or either of them, the volume and velocity of the air current circulating through the chambers, screen 140 and inlet and outlet openings may be varied, and the classification effect can be regulated. Since the screen ring is made of detachably connected sections, and the sections are detachably connected to the baffle plate, rings having openings 145 of various sizes may be used according to the grade of the product to be separated.

It will be understood that the invention is not limited to the specific embodiment shown, and that various deviations may be made there-

from without departing from the spirit and scope of the appended claims.

What is claimed is:

1. An air separator for grading materials comprising, in combination, separating and settling chambers having inlet and outlet openings between them, means to cause air to circulate and whirl through said chambers and openings and move up in the separating chamber and down in the settling chamber, a rotary distributor for delivering material to be graded into the path of the up-moving air in the separating chamber, a rotary baffle plate extending beneath the entire outlet opening, and a screen on said baffle plate extending from its periphery nearly to the wall of the separating chamber for obstructing passing of heavier particles through the outlet opening while permitting fines to pass through said opening. 80
- 10 2. An air separator for grading materials comprising, in combination, separating and settling chambers having peripheral lower inlet and central upper outlet openings between them, means to cause air to circulate and whirl through said chambers and openings and move up in the separating chamber and down in the settling chamber, a shaft, a distributor and a solid plate on the shaft for baffling said outlet opening, and a screen ring rotating with the baffle plate and located between its periphery and the wall of the separating chamber to lie outside of said central outlet opening for obstructing passing of heavier particles through the outlet opening while permitting fines to pass therethrough. 90
- 20 3. An air separator for grading materials comprising, in combination, separating and settling chambers having peripheral lower inlet and central upper outlet openings between them, means to cause air to circulate and whirl through said chambers and openings and move up in the separating chamber and down in the settling chamber, a shaft, a distributor and a central baffle plate on the shaft below said outlet, and a screen ring on the edge of and rotating with the baffle plate and projecting therefrom toward the wall of the separating chamber, said ring being formed of sections. 95
- 25 4. An air separator for grading materials comprising, in combination, separating and settling chambers having peripheral lower inlet and central upper outlet openings between them, means to cause air to circulate and whirl through said chambers and openings and move up in the separating chamber and down in the settling chamber, a shaft, a distributor and a central baffle plate on said shaft below said outlet, and a screen ring detachably connected to the baffle plate and projecting outward in substantially the plane thereof toward the wall of the separating chamber to lie outside of said central upper opening. 100
- 30 5. An air separator for grading materials comprising, in combination, separating and settling chambers having inlet and outlet openings between them, means to cause air to circulate and whirl through said chambers and openings and move up in the separating chamber and down in the settling chamber, and a rotary distributor for delivering the material to be graded into the path of the up-whirling air in the separating chamber under the influence of centrifugal force, said distributor having a polygonal perimeter, that the materials may leave the distributor at various distances from the center of the distributor and be delivered into different zones in the separating chamber. 105
